United States Patent Office

Des. 217,531
Patented May 12, 1970

217,531

HEAD ORNAMENT

Jocelyn D. Miller, Scottsdale, Ariz., assignor to Paul M. Piscano and Tamara R. Piscano, both of Tarzana, Calif.

Filed Dec. 30, 1968, Ser. No. 15,155

Term of patent 14 years

Int. Cl. D2—01

U.S. Cl. D2—250

FIG. 1 is a front perspective view of a head ornament showing my new design; and

FIG. 2 is a side elevational view thereof;

FIG. 3 is a side elevational view thereof.

The broken line showing of a head in FIG. 1 is merely for illustrative purposes.

I claim:

The ornamental design for a head ornament, as shown.
